* cited by examiner

Primary Examiner—Ian Simmons*Assistant Examiner*—Dana Sipos(74) *Attorney, Agent, or Firm*—Knobble Yoshida & Dunleavy, LLC(57) **CLAIM**

The ornamental design for a “portion of container,” as shown and described.

DESCRIPTION

FIG. 1 is a perspective view showing my new design;

FIG. 2 is a front elevational view;

FIG. 3 is a rear elevational view;

FIG. 4 is a left side elevational view;

FIG. 5 is a right side elevational view;

FIG. 6 is a top plan view; and,

FIG. 7 is a bottom plan view.

The broken lines in the drawings are for illustrative purposes only and form no part of the claimed design.
